W. A. COPELAND,
BASS ATTACHMENT FOR ZITHERS,
APPLICATION FILED JAN. 17, 1917.

1,246,058.

Patented Nov. 13, 1917.

UNITED STATES PATENT OFFICE.

WILLIAM A. COPELAND, OF BROOKLINE, MASSACHUSETTS, ASSIGNOR TO THE PHONO-HARP COMPANY, OF EAST BOSTON, MASSACHUSETTS, A CORPORATION OF MAINE.

BASS ATTACHMENT FOR ZITHERS.

1,246,058.

Specification of Letters Patent. Patented Nov. 13, 1917.

Application filed January 17, 1917. Serial No. 142,887.

To all whom it may concern:

Be it known that I, WILLIAM A. COPELAND, a citizen of the United States, residing at Brookline, in the county of Norfolk 5 and State of Massachusetts, have invented new and useful Improvements in Bass Attachments for Zithers, (Case B,) of which the following is a specification.

This invention relates to zithers and has 10 for its object to provide a simple attachment for use in connection with groups of bass strings, so that an operator can cause a selected group to sound in accompaniment to a melody produced on a group of melody 15 strings.

On the drawing,—

Figure 1 illustrates a zither equipped with an attachment embodying my invention.

Fig. 2 represents a section on the line 2—2 20 of Fig. 1.

Fig. 3 illustrates in section another form of striker differing somewhat from that shown in Fig. 2.

Fig. 4 represents a perspective view of 25 the second form of striker or hammer.

The particular style and shape of the body portion of the zither to which my attachment is applied is immaterial, and it is likewise immaterial whether the melody 30 strings are plucked by the fingers of the player or are caused to sound by the aid of hammers. As exemplifying one form of zither with which the attachment may be used, Fig. 1 illustrates a zither formed in 35 the usual manner and having the apertured sounding board 5, which forms the upper wall of a hollow body. The melody strings, which are arranged to furnish either a diatonic scale of any key or a chromatic scale, 40 are indicated at 6. The chord strings are arranged in groups which are tuned to furnish the tonic, dominant and subdominant chords of a key, and an additional chord such for example as bass *d*, *a*, *d* and *f*♯ if 45 the tonic chord be in the key of C. In fact, in an instrument having the melody strings arranged in a chromatic scale, I may employ twelve groups of chord strings arranged as described in Letters Patent to 50 Marx No. 1,190,782, dated July 11, 1916. As indicated, however, there are four groups 7, 8, 9 and 10 of chord strings, each group consisting of a fundamental bass string, and three additional strings to produce a triad.

My attachment consists of a plurality of 55 spring strikers or hammers, one for each group of chord strings, and a separate support or bridge for each striker, as indicated at *a*, *b*, *c* and *d* in Fig. 1. Each bridge 11 is preferably, though not necessarily, 60 formed of wood and has integral standards 12 which support it above the plane of the chord strings which it crosses. Each bridge or support straddles but one group of strings, and the several groups are spaced sufficiently to permit the standards to be located between them without interfering with the vibration of the strings. The bridges are secured directly to the sounding board by 65 screws 13 at points between the ends of the strings but preferably near the front end 70 of the zither. The bridges are staggered to prevent undue lateral separation of the groups of chord strings. Secured to the top of each bridge or support is a spring striker 75 which normally occupies a position above and out of engagement with the associated strings, and which, when raised and then released, will by its resiliency and momentum descend and strike the strings therebelow. As shown in Figs. 1 and 2, the 80 striker includes a leaf spring 130 secured at one end to the bridge or support by screws 14, and at its free end to a wooden fingerpiece 15 by screws 16. The front end of the 85 fingerpiece is beveled on its under side, as at 17, and it has cemented or otherwise secured thereto a head 18 which may be made of such material as lead or wood, although I prefer relatively hard felt. The fingerpiece 90 and the head are of sufficient width, so that the head in its descending movement will impinge upon all of the strings and cause them to produce their proper musical notes, simultaneously or substantially so. 95 The leaf spring is preferably fairly stiff and as wide as the fingerpiece.

In playing the instrument, the operator with the thumb of his left hand may from time to time lift and release one or the other of the hammers to produce an accompaniment to the melody played upon the scale strings.

Instead of having a separate fingerpiece, a beveled head 19 may be secured by screws 105 20 to the under side of the free end of the spring, as shown in Fig. 3, so that the part 19 will serve both as a head, and also as a

fingerpiece to be lifted by the operator. The springs may be straight as in Fig. 2 or curved as in Figs. 3 and 4.

Having thus explained the nature of my said invention and described a way of making and using the same, although without attempting to set forth all of the forms in which it may be made or all of the modes of its use, what I claim is:

- 10 1. The combination with a zither having spaced groups of chord strings, of a plurality of bridges or supports affixed to the sounding board of the zither, each bridge straddling a group of chord strings, and a striker carried by each bridge, each striker consisting of a leaf spring attached at one end to the associated bridge and extending longitudinally of the strings therebeneath and normally out of contact with such strings, and a head carried by the free end of such spring and extending transversely of the strings of the group.
- 15
- 20

Copies of this patent may be obtained for five cents each, by addressing the "Commissioner of Patents, Washington, D. C."

2. The combination with a zither having spaced groups of chord strings, of a plurality of bridges or supports affixed to the sounding board of the zither, each bridge straddling a group of chord strings, and a striker carried by each bridge, each striker consisting of a leaf spring attached at one end to the associated bridge and extending longitudinally of the strings therebeneath, a fingerpiece secured to and carried by the free end of the spring and a head on the under side of the fingerpiece and wide enough to impinge upon all the strings of the associated group, said head, when raised and released, being caused by the resiliency of the spring and its own momentum to descend and strike the chord strings therebeneath.

In testimony whereof I have affixed my signature.

WILLIAM A. COPELAND.
